UNITED STATES PATENT OFFICE.

ANDREW BONGIRNO, OF BROOKLYN, NEW YORK.

DESIGN FOR A TOY CAT.

Application filed October 28, 1922. Serial No. 4,145. Term of patent 3½ years.

To all whom it may concern:

Be it known that I, ANDREW BONGIRNO, a subject of the King of Italy, residing at Brooklyn, in the county of Kings and State of New York, have invented a new, original, and ornamental design for toy cat, of which the following is a specification, reference being had to the accompanying drawings, forming part thereof, in which—

Fig. 1 is a side elevation, and

Fig. 2 is a front view of a toy cat embodying my new design.

I claim:

The ornamental design for a toy cat as shown.

ANDREW BONGIRNO.
